APPARATUS FOR TURNING CIGARETTES RIGHT SIDE UP AS THEY ARE FED TO THE
PACKING MACHINE

Original application filed July 1, 1929, Serial No. 375,264, and in Germany May 23, 1928. Divided and
this application filed May 29, 1930. Serial No. 457,451.

This invention relates to process and apparatus for turning cigarettes right side up as they are fed to the packing machine.

The present invention is a division of my
5 co-pending application, Ser. No. 375,264,
filed July 1, 1929.

According to the present invention a certain number of the cigarettes as they are carried forward continuously by the feed
10 device is held by means of a mechanical device in a position of apparent rest in relation to an observation post incorporated with the control of a turning device so that the operation of the turning device can be
15 effected with certainty, notwithstanding the continuous movement of the cigarettes.

In the preferred form the mechanical device comprises a frame having an aperture therein through which the cigarettes are ob-
20 served and an operating appliance in the frame for enabling the turning of any desired cigarette seen through the aperture, said frame being adapted to move forward simultaneously with the cigarettes and to
25 return after a certain movement to its original position.

The appended drawings show by way of example a constructional form of the invention and

30 Fig. 1 is a diagrammatic side view of the device.

Fig. 2 is a plan of the righthand part of Fig. 1.

Fig. 3 is a section through Fig. 1 on the
35 line A—B.

Fig. 4 is a side view of one part taken from Fig. 1.

The cigarettes to be packed are conveyed in the usual manner by a device, which, in
40 the examples shown, consists of a chain moving at a uniform speed. The links 10 of this chain are held together by pins 11.

The links 10 are provided with grooves 12, in which the cigarettes 13 lie in an oblique
45 position. The grooves 12 have raised edges indicated by 14, Fig. 1, against which the cigarettes rest. At suitable places along the line of travel one or more stops 15 are placed, these being vertically movable up
50 and down in guides 16, and so placed that

when in the upward position they engage the cigarette as it moves along, straightening it and giving it a turn of 180°.

Above the conveying device 10, 11 for the cigarettes 13 a frame 26 is provided, this 55 frame being movable to and fro in the same direction as the conveyor device. In the middle of the frame is an aperture 26¹ through which a certain number of cigarettes—in the actual example eight, are visible. The frame moves forward at the same speed as the cigarettes themselves. For this purpose the chain is best provided at suitable intervals, that is to say at each eighth link, with vertically movable pins 27. 60 These pins are controlled by guides 28, 28' in such manner that when the frame 26 is required to start moving with the cigarettes, as shown at the right-hand stop 27 in Fig. 1, they are raised upward. They then come 70 up against the frame 26, and as they are held in the upward position, and move forward with the chain, they carry the frame along at the same speed. The frame consequently shows always the same number of cigarettes through its aperture, whilst those lying further forward or back on the conveyor remain concealed. As soon as the stop 27 leaves the track 28, and passes on to the guide track 28', it drops into the position shown to the left of Fig. 1 thereby releasing the frame 26, which by means of springs, or, as shown in the example illustrated, weights 29 attached to cords 31 running on pulleys 30, can be brought back into 80 its original position, where it comes up against the next stop 27 that has meanwhile been raised into the working position and is ready to carry it forward again. The eight cigarettes 13, visible through the aperture in 90 the frame 26, therefore remain without motion in relation to the frame and it is easy for the observer to keep his eye on them for a time without undue fatigue; they remain in the frame until the whole conveyor mechanism has moved forward to the extent of eight cigarettes.

On the frame 26 eight keys 33 are placed and each of these keys is adapted to release the turning device. For this purpose the 100

keys 33 are connected to electric circuits 35¹, 35² etc. which are closed by pressure on the keys. The wires 35¹, 35², and so on are jointly connected to one pole of a battery 36^a, the other pole of the battery being connected to a return wire. Each of the wires 35¹, 35² etc. leads to a roller or rubbing contact 37 made of conductor material which is placed at the periphery of a revolving disc 36 driven by any form of power. There are eight of these contacts working on the same axis and each one of them contacts with a slip ring 38 on the periphery of the disc 36.

15 Within the disc 36 are a number of electromagnets 39, Fig. 3, in the present instance 24 altogether, that is to say three times as many as the number of push keys. The number of electromagnets being three times 20 as large as the number of wires 35¹, 35² and so on, the slip rings 38 are subdivided into three parts disposed around the periphery of the disc 36. Each one of the electromagnets 39 is connected by a conductor 40 to one 25 of the eight slip rings 38. Two other discs, 41 and 42 are permanently connected to disc 36. Disc 41, which is of smaller diameter than 36 and 42, the latter preferably being equal, has on its periphery a coating of conductor material 43, connected by wires 44 with the adjacent ends of the magnet windings of all the electromagnets 39. In contact with the coating 43 is a roller or rubbing contact 45, connected to the return wire 35 of the electric circuit.

30 In the disc 42 are longitudinally slidable magnet armatures 46 placed opposite to the electromagnets on disc 36, so that these armatures 46 are likewise 24 in number. 35 The armatures 46 are generally arranged in the positions shown in Fig. 3, so that as they pass by the free end of an elbow lever 48 connected to the stop 15 of the turning device they hold the lever in such a position that the stop 15 of the turning device does not project into the path of travel of the cigarettes. When, however, the circuit of one of the electromagnets 39 is closed by pressing down the appropriate key 33, the 40 respective armature 46 is attracted, so that on the subsequent passage of the armature 46 the lever 48 is released and is moved by the action of a spring 50 into such a position that the stop 15 is in the raised position 45 causing it to come up against the cigarettes 13 as it moves forward and to give it a turn of 180°. The speed of rotation of discs 36 and 42 is so calculated that the passage of the attracted armature 46, and consequently 50 the release of lever 48 shall occur at the moment in which the particular cigarettes 13, the incorrect position of which gave cause for pressing down the key 33 and thereby closing the circuit, has arrived in 55 front of the stop 15 of the turning device,

so that in every case it is the right cigarette that is turned.

For the purpose of effecting the return movement of the attracted armature 46, there is placed by the side of disc 42 an inclined surface 51 (Fig. 4) which has effect, as disc 42 continues to rotate, of pushing the armatures 42 back into the position shown in Fig. 3.

The scope of the invention is not limited to turning devices of the kind represented in the drawings. It can also be used in conjunction with turning devices of other kinds, for example with turning devices designed to grasp the cigarettes directly on their faces and to turn them over. Further, also automatic means utilizing the sensitivity of photo-electric cells, selenium cells or other devices may be used for turning the cigarettes right side up.

I claim:—

1. A device for enabling the turning of cigarettes right side up as they are fed to a packing machine comprising a frame having an aperture therein through which the cigarettes are observed; and on operating appliance in the frame for enabling the turning of any desired cigarette seen through the aperture, said frame being adapted to move with the cigarettes.

2. A device for enabling the turning of cigarettes right side up as they are fed to a packing machine comprising a frame having an aperture therein through which the cigarettes are observed; an operating appliance in the frame for enabling the turning of any desired cigarette seen through the aperture, said frame being adapted to move with the cigarettes; a cigarette conveyor; and a plurality of engaging pins for moving the frame forward simultaneously with the cigarettes.

3. A device for enabling the turning of cigarettes right side up as they are fed to a packing machine comprising a frame having an aperture therein through which the cigarettes are observed; an operating appliance in the frame for enabling the turning of any desired cigarette seen through the aperture, said frame being adapted to move with the cigarettes; a cigarette conveyor; a plurality of engaging pins for moving the frame forward simultaneously with the cigarettes; and means for releasing and returning the frame back to its original position.

4. A device for enabling the turning of cigarettes right side up as they are fed to a packing machine comprising a frame having an aperture therein through which the cigarettes are observed; an operating appliance in the frame for enabling the turning of any desired cigarette seen through the aperture, said frame being adapted to move with the cigarettes; a cigarette conveyor

adapted to be moved intermittently so that the cigarettes remain motionless for a short period to allow for observations; and a plurality of engaging pins for moving the frame forward simultaneously with the cigarettes.

5. An apparatus for enabling the turning of cigarettes right side up as they are conveyed to a packing machine, comprising in combination with the conveying means for continuously conveying the cigarettes an operating appliance operatively connected with said conveying means and adapted to control a turning device.

10 In testimony whereof I affix my signature.
